TEXTILE FABRIC

Paul Metzger, Basel, Switzerland

Application April 22, 1939, Serial No. 269,518

2 Claims. (Cl. 139—385.5)

This invention relates to a textile fabric adapted for use in articles of wearing apparel that have fold lines such as collars and cuffs.

The fabric of this invention is primarily for use as a lining ply insertion in a multiply article of wearing apparel having a fold line which article is stiffened by adhesively uniting the plies together.

The stiffened article of wearing apparel is provided between each two layers of washable material with an adhesive-containing stiffening insertion which cements the two layers of washable material together, the said stiffening insertion being provided with pores passing through the same, the size and disposition of which in at least one position, serving as folding position, are such that the article of wearing apparel at this position is softer than at the remaining parts, in order to enable easy folding to be effected.

Examples of stiffening means for the lining ply insertion of this invention are fabrics woven from masses which are soluble or capable of swelling or can be softened by heat, for example cellulose derivatives, with or without softeners, natural or artificial resins and the like, which after being inserted are softened under pressure by treatment with dissolving or swelling agents or by heat and are thereby caused to adhere to the outer plies. This woven fabric need not necessarily consist entirely of cellulose derivatives, but may also consist of mixed fabrics, for example of acetate silk and cotton.

The lining ply of this invention may be inserted in any desired manner between the pieces of material to be stiffened. Threads may lie for example parallel or crossed and fabrics may be so arranged that their threads lie parallel or, for example, diagonally to the threads of the article of wearing apparel. Fabric insertions may for example be of the usual rectilinear form or may also be woven in conical form.

Instead of being discontinuous, the lining ply insertion of this invention may be provided at the folding position with spaces, for example holes, slits and the like. If threads, strips, cuttings and the like are employed, these may be entirely or partially omitted in the folding position or consist of weaker material at this point.

If the lining ply insertions consist of fabric, composed entirely of cellulose derivative threads for example, a part of the threads may be omitted or consist of thinner material at the folding position. In the case of mixed fabrics, cellulose derivative threads may be entirely or partially

omitted or if desired consist of thinner material at the desired position.

Finally the folding line in all the hereinbefore described cases may be produced by preventing the insertion from developing a stiffening effect at the position in question by inhibiting or weakening its adhesive action. This may be effected by protecting the insertion at the folding position from the action of the dissolving or swelling agents during the treatment with the said agents of the article of wearing apparel containing the insertion. In certain circumstances the article of wearing apparel, in which the insertions have already been cemented, may also be subjected to a treatment whereby adhesion at the folding position is again removed by completely dissolving the cellulose derivative at this point.

Obviously the folding position may also be produced by any desired combinations of the known weakening methods employed in the weaving industry and the hereinbefore described methods.

One method of procedure in the manufacture of the article of wearing apparel in which the textile fabric of this invention is to be employed as an insertion is first to complete the same from outer layers and at least one insertion and then to moisten the completed article with a solvent or swelling agent for the adhesive material contained in the insertion and thereafter to subject the article to compression, if necessary with the application of heat. An alternative procedure, however, is first to superimpose sheets of the requisite material, i. e., the outer material and the insertion or insertions, then to saturate the superimposed sheets with the solvent in question, with the aid of rollers, to pass the sheets so joined together over hot rollers and in this way to produce an end product, from which articles of wearing apparel adapted to be laundered having a prepared folding line, for example collars and the like, may be produced by stamping out, after which the articles need only be provided with buttonhole or marginal seams. If collars or cuffs or, for example, shirt fronts for sewing on to shirts are to be made, the threads of adhesive material in the stiffening insertion can be likewise entirely omitted or replaced by threads of non-adhesive material at the edges which are to remain soft.

The materials to be cemented together may be cut in sheets of about the width of a single article of wearing apparel and be joined together. An alternative procedure, however, is to keep the sheets so wide that several articles lying side by side can be cut out, as is for example disclosed

in Swiss patent specification No. 158,520. The sheets may, for example, be so prepared that in the folding lines *c* and *d* of Fig. 2 of the said patent specification the stiffening insertion is either entirely omitted or the adhesive threads are entirely or partially omitted.

By way of example, reference is to be had to the accompanying drawing wherein:

Figure 1 shows a multiply article of wearing apparel with the outer ply broken away to show one type of lining ply insertion of this invention;

Fig. 2 is a sectional view through Fig. 1 to illustrate the weave of the lining ply;

Fig. 3 shows a multiply article similar to Fig. 1 with another type of construction for the lining ply;

Fig. 4 is a sectional view taken on the line 4—4 of Fig. 3;

Fig. 5 shows a multiply article similar to Fig. 1 showing another type of lining ply insertion of this invention; and

Fig. 6 is a sectional view taken on the line 6—6 of Fig. 5.

Figures 1 and 2 show a multiply article of wearing apparel such as a collar or cuff having outer plies 18 and 14 of any suitable material used in the construction of such articles and a lining ply 12 inserted between the outer plies. There is a fold zone 13 for the article. To make the article readily foldable at this fold zone the lining ply is woven in the following manner:

The weft threads 14 of the lining ply are all cotton or any suitable material other than cellulose derivative threads. The warp threads 15 and 16 are of cotton and acetate respectively arranged alternately or in spaced groups in any well known manner. At the area of the fold zone the warp threads are entirely omitted. Thus, when the plies are joined together adhesively by a suitable solvent and heat and pressure in a manner well known in the art, the plies will not be

adhesively united in the area of the fold zone, and the article will be more readily foldable.

In Figures 3 and 4 the lining ply is woven of the same materials in the warp and weft as in Fig. 1, but in making the article of wearing apparel the lining ply is completely omitted in the area of the fold zone.

In Figures 5 and 6 the same weft and warp threads are used as in Fig. 1, but in the area of the fold zone all cotton warp threads are used instead of alternate cotton and acetate threads as in the rest of the lining. This weave accomplishes the same easily foldable fold zone in the finished article, but it is stronger than the the lining of Fig. 1 because no threads are omitted.

The material of this invention may be woven in a flat rectilinear form or may be woven conically depending upon the type of fold line desired. With a curved fold line a conical weave will be used.

This application is a continuation-in-part of my pending application Serial No. 26,502, filed June 13, 1935.

What I claim is:

1. A lining for a collar and cuff comprising a textile body having a fold zone, said body having woven therein a substance which is initially non-cementitious but has the inherent property of being made cementitious, the fold zone of the lining being woven from yarns free from cementitious material.

2. A lining for a collar comprising a curvilinear textile body having a fold zone, said body having woven therein a substance which is initially non-cementitious, but having the inherent property of being made cementitious, the fold zone of the lining being woven from yarns free from cementitious material.

PAUL METZGER. 40
